UNITED STATES PATENT OFFICE.

FREDERIC THÉVOZ, OF GENEVA, SWITZERLAND.

PRESS.

Application filed December 22, 1925. Serial No. 77,160.

This invention relates broadly to the art of printing and especially to that branch of the printing art wherein different colors or patterns are successively applied to the sheet to be printed to produce a complete composite impression. More particularly the invention relates to devices by which such composite impression may be obtained and has for its object the provision of a plurality of devices applying different impressions arranged in series with conveying and drying mechanism for a sheet therebetween. In accordance with the invention a plurality of printing mechanism or the like are adapted to apply different impressions respectively to sheets, say of paper, and these mechanisms are arranged in series with suitable conveying and drying devices for the paper between the respective printing mechanisms. The conveying and drying devices between each two presses may take the form of a plurality of reciprocating, constantly rotating endless bands and devices by which the sheets are transferred from one band to an adjacent one whereby the sheets are given a circuitous path or travel from one printing mechanism to the next in the series. During the transportation of the sheets upon the bands they may be subjected to a drying operation by blasts or jets of air, if desired of predetermined temperature, and these blasts of air may be relied upon, in some instances, to maintain the sheets in contact with the conveying devices particularly when the endless bands are traveling in a substantially vertically direction.

In order that the invention may be clearly understood and readily carried into effect the same will now be described more fully with reference to the accompanying drawings illustrating a preferred embodiment thereof, in which:

Figure 1 is a somewhat schematic view showing a plurality of impression applying devices between which the sheets upon which the impression is made are conveyed and dried in accordance with the present invention.

Figures 2, 3 and 4 are views illustrating various positions taken by the different conveying and drying devices in the transfer of the sheets between the printing mechanisms.

In the drawings only two ink applying mechanisms are illustrated but it will be understood that this number may be multi-

plied according to the number of colors or impressions required to make up the composite product.

A stack *a* of individual sheets *a'* is brought to the first printing mechanism upon a truck or the like *b* from whence the support *b'* may be engaged with vertically moving conveying devices *c* adapted to gradually raise the stack, as indicated at *A*, for the removal of the topmost sheet. From the stack the topmost sheet is removed by any suitable devices such as grippers or a suction device *d* and is transferred to the inclined feeding table *e* down which the sheet moves either under the action of gravity or by means of traveling tapes or rollers to the pressure cylinder *f* where it is engaged in known manner by grippers or the like and is conveyed into contact with the engraving cylinder *g*. The cylinder *g* is supplied with ink, as will be understood, by the inking roll *g'* turning constantly in the ink container *g''* and the requisite amount of ink on the cylinder *g* is determined by the controlling element *g''*. From the pressure roll *f* the sheet is transferred in known manner to the conveying cylinder *h* from whence it is transferred to the traveling conveyer *i* as shown in Figure 2. The sheet is not only conveyed along the length of the conveyer by means say of the traveling endless belt *i'* but the conveyer as a whole reciprocates from a position at the right immediately beneath roll *h*, as shown in Figure 2, to a position at the left as shown in Figure 1. Thus the sheet from roll *h* Figure 2, is fed to the conveyor *i* which immediately commences moving to the left in the direction of the arrow *x*, the endless belt *i'* in the meantime conveying the paper to the left end as viewed in Figure 2 and projecting it over the end of the conveyor where it is engaged by the gripper *j*. The conveyor *i* at once moves to the right as shown by the arrow *x'* allowing the sheet to be directed downwardly either by its own weight or by a pivotal action of the gripper *j* about its pivot *j'* to be picked up by the conveyor *k*. So soon as the sheet is supported by the conveyor *k* it is released by the gripper *j* and the traveling belt *k'* conveys the paper to the right (Figure 3) for engagement by the gripper *l* similar in every respect with the gripper *k*. In its passage to the gripper *k* the ink is subjected to a drying operation by air *m* blown from a plurality of jets *m'*.

When the sheet is engaged by gripper *l*, conveyor *k* moves to the left (Figure 4) in the direction of the arrow *y* and during this time the conveyor *i* may also be moving to the left and conveying another sheet *A'* to the gripper *j*. Thus the conveyor *k* is moving to the receiving position for another sheet and this movement permits the transfer of the sheet *a'* (Figure 4) to an endless belt *n* by means of gripper *l*. By means of the belt *n* the sheet is conveyed, if desired, beneath another blast of air *o*, beneath, if desired, a walk *p* for an attendant of the presses and upwardly to the feeding table *E* of the next press, where the same operations are repeated.

It will be observed that by the time the sheets have passed beneath the drying devices *m* and *o* they are at the comparatively low level *N* while the table *E* is at a much higher level. To convey the sheets to the higher level the belt *n* is deflected upwardly at the pulleys *n'*, *n²* and between them and the pulley *n³* travels in a direction only a few degrees from the vertical. A plurality of jets of air *q* are directed against the belt and this blast of air is availed of not only to contribute to the drying of the ink but also aids naturally in maintaining the contact of the sheet within the conveyor whereby the sheet may be carried upwardly and deflected onto the table *E* by the deflector *r*. If desired, additional endless tapes *s* may be driven in synchronism with the belt *n* to assist in holding the sheets in contact with the belt *n* in its upward travel.

By the structure described individual sheets may have a composite impression applied thereon by a process which does not involve manual steps and the sheets may be transported and simultaneously dried in transit between the impression applying devices.

The various actuating mechanisms for the gripping devices, printing rolls and traveling belts have not been illustrated in the drawings since these may take any desired form and are well known in the art.

The invention is not to be deemed limited to the precise form or combination of elements illustrated in the drawing as going to make up the composite impression apply-

ing device as a whole, but various combinations and sub-combinations of the essential features may be made without departing from the spirit and scope of the invention.

What I claim is:

1. In an apparatus for forming a composite impression upon a sheet, in combination, a plurality of reciprocating endless bands between each two devices, means to transfer a sheet from one band to another, means to direct air against the sheet when on a band, and means to transfer the sheet from a band to a succeeding device. 65

2. In an apparatus for forming a composite impression, in combination, a plurality of proximate devices for applying impressions arranged in series, a plurality of superimposed reciprocating endless bands between each two devices, means to transfer a sheet from one band to another, means to direct air against the sheet when on a band, and means to transfer the sheet from a band to a succeeding device. 70

3. In an apparatus for forming a composite impression, in combination, a plurality of proximate devices for applying impressions arranged in series, a plurality of superimposed reciprocating endless bands between each two devices, means to transfer a sheet from a device to the uppermost band, means to direct air against the sheet when on a band, and means to transfer the sheet from the lowermost band to a succeeding device. 75

4. In an apparatus for forming a composite impression, in combination, a plurality of proximate devices for applying impressions arranged in series, a plurality of superimposed reciprocating endless bands between each two devices, means to transfer a sheet from a device to the uppermost band, and endless band to receive the sheets from the lowermost reciprocating band extending partly in a substantially vertical direction 80 means to direct jets of air against the sheets when on the substantially vertical portion of the band, and means to transfer a sheet from the last named portion to a succeeding device. 85

This specification signed this 20th day of Nov., A. D. 1925.

FREDERIC THÉVOZ.
